UNITED STATES PATENT OFFICE

2,583,149

EVAPORATIVE FLUID COOLING APPARATUS

Hyman Malkoff, Trenton, N. J., assignor to
 Kramer Trenton Company, Trenton, N. J., a
 corporation of New Jersey

Application October 19, 1948, Serial No. 55,280

9 Claims. (Cl. 62—139)

1

This invention relates to evaporative fluid cooling apparatus which is designed to chill and, in the case of gases to condense, fluids in pipe coils, or the like; the invention being especially adapted for embodiment in condensers of refrigerating apparatus, although it is also adaptable to the cooling of liquids such as water and oil in various types of machinery and industrial apparatus.

The invention is directed more particularly to means for circulating the cooling water through the apparatus, and has for an object to provide such means which cause a high rate of circulation without corresponding increase in power consumption.

Another object is to provide such an apparatus in which the water is circulated by a driven impeller or the like and which includes means for preventing the water acted upon by the impeller from being churned or swirled in a rotary direction.

Another object is to provide such an apparatus in which the water level is automatically maintained by the supplying from an outside source of small increments of fresh water to compensate for slight losses occurring during operation.

Another object is to provide such an apparatus which includes means for automatically periodically removing a portion of the water which has been recirculated with consequent increase in its salt concentration, together with automatic means for periodically supplying fresh water to replace that which has been thus removed.

Another object is to provide such an apparatus in which the means for periodically removing a portion of the water is of the siphon type, and the means for supplying quantities of fresh water is governed by a valve which is controlled by the level of the water in the apparatus.

Another object is to provide such an apparatus in which the water is caused to drop or rain upon the coil from a considerable number of orifices in a vessel located above the coil, the size of the said orifices being sufficient to permit the water to pass therethrough as a liquid as distinguished from being atomized.

Another object is to provide such an apparatus which includes a power driven fan that promotes vaporization of part of the water precipitated upon the coil and increases the chilling effect upon the fluid within the coil.

A further object is to provide certain improvements in the form, construction and arrangement of the parts whereby a substantial increase in efficiency and economy in operation is secured and the above mentioned objects, as well as

2

others inherent in the invention, are satisfactorily attained.

Practical embodiments of the invention are represented in the accompanying drawings in which:

5 Fig. 1 represents a partly broken away and partly sectional elevation looking at the fan end of the apparatus, which is in the form of a unit adapted to be suspended from a ceiling;

Fig. 2 represents a partly broken away and 10 partly sectional side elevation of the same;

Fig. 3 represents a detail section taken in the plane of the line III—III of Fig. 1, looking in the direction of the arrows;

Fig. 4 represents a detail transverse section 15 taken in the plane of the line IV—IV of Fig. 2;

Fig. 5 represents a view similar to Fig. 1, but showing a modified form of the apparatus;

Fig. 6 represents a view similar to Fig. 2, but showing the said modified form;

20 Fig. 7 represents a side elevation, partly broken away and partly in section, of a second modified form which is adapted for floor installation;

Fig. 8 represents an elevation, partly broken 25 away and partly in section, taken at right angles to Fig. 7; and

Fig. 9 represents a detail elevation, partly broken away and partly in section, showing a third modification which is also adapted for floor installation.

30 Referring to Figs. 1 to 4, the apparatus is presented in the form of a unit and has a casing which is preferably composed of metallic plates or panels, such as galvanized steel, and includes a top 1, sides 2 and 3, and a face plate 4, the said parts being firmly secured to each other as by welding or riveting. Channel iron brackets 5 and 6 are fixed to the top 1, as by riveting or welding, and are designed to cooperate with any suitable type of ceiling hangers for suspending the unit as a whole.

35 To the underside of the top 1 a water distributing pan 7, which may be composed of sheet metal, is fastened, preferably by welding, and from the said pan depend a pair of coil header plates 8 and 9, which are suitably apertured to receive the bends of a pipe coil 10, which is preferably composed of copper or aluminum tubing and consists of a plurality of sinuous sections 40 having their upper ends fitted into the side of a fluid inlet pipe 11 and their lower ends fitted into the side of a discharge pipe 12. It will be understood that the connection between the coil sections and the pipes 11 and 12 is fluid tight, and 45 the said pipes are snugly fitted through holes in

the face plate 4 so that inlet pipe 11 may be connected with any source of fluid supply, such, for instance, as the discharge of a compressor in a refrigerating apparatus, while the discharge pipe 12 may be connected with a suitable receptacle, such, for instance, as the receiver of a refrigerating apparatus.

A combined reservoir and water catch pan 13, 14, preferably composed of sheet metal, such as galvanized steel, embraces the lower part of the casing and is firmly secured to the casing sides 2, 3, in any suitable manner, such as by welding or riveting. In the drawing the said element 13, 14, is illustrated as of unitary construction, but it will be understood that it may be composed of several parts suitably fixed to each other.

The reservoir 13 extends across the full width of the front or face plate of the casing and, at the lower portion of one side thereof is fitted a small chamber 15, which may be designated a pump return tank, which tank 15 is connected to water distributing pan 7 by a vertically disposed water delivery tube 16, so that water may be forced from tank 15 to pan 7.

The bottom of pan 7 is perforated preferably in the form of a large number of nozzles 17, which are preferably of sufficient diameter, e. g., one eighth of an inch or larger, so as to permit water to pass therethrough without being atomized, and it will be clear that water passing through the said nozzles will descend upon all parts of coil 10 and that the water passing downwardly through and dripping from the coil will be trapped by the catch pan 14 and returned to the reservoir 13.

Uprising from pump return tank 15 is a cylindrical pump housing 18 and the upper end of said housing is covered by a base plate 19, which serves to support an electric pump motor 20, the drive shaft 21 of which motor projects downwardly through housing 18 and carries at its lower extremity a bladed impeller 22. Fixed in the housing 18 above the impeller 22 is a sleeve 23 which has a hub 24 that may, if desired, serve as a bearing for shaft 21, although the shaft is so short as not to require a bearing, and a series of radial vanes 25, which latter are parallel with the shaft 21. A circumferential series of holes 26 is formed in the wall of the pump housing 18 immediately above the sleeve 23 to permit the ingress of water.

The face plate 4 of the unit casing is provided with a large central aperture 27 within which is positioned a fan 28 that is mounted on a drive shaft 29 of an electric motor 30, which latter is supported by four bracket arms 31, that are suitably fixed to the motor, as indicated at 32, and are secured to the face plate as by bolts 33. It will be understood that pump motor 20 and fan motor 30 are connected to any suitable source or sources of electric current, and it may be noted that the said motors may be subject to manual control only, as by suitable switches (not shown), and/or that the operation of either or both may be subject to automatic control by pressure or thermostatic switches in a manner which is well understood by those conversant with the refrigeration industry and is not illustrated herein as it constitutes no part of the present invention.

At the end of the casing opposite the fan are secured upper and lower supports 34, 35, to which are fixed a series of vertically disposed eliminator blades 36, which are of zigzag form in cross section, as shown in Fig. 4, the purpose of the said

blades being to separate entrained water globules from the air driven through the casing by the fan so that the said water may fall into catch pan 14 and be returned to reservoir 13.

5 A pipe 37 leads from any suitable source of water supply to reservoir 13 and the said pipe is opened and closed by a valve 38, which is governed by a float 39, the construction of said float valve being a matter of such common knowledge among mechanics and engineers as to call for no further explanation or description. A siphon tube 40 is also fitted in the wall of reservoir 13 for a purpose to be hereinafter described and a water overflow pipe 41 pierces the bottom of the said reservoir at 42 to provide against the maintenance of too high a level of water therein.

In operation, the reservoir is filled by supplying water through pipe 37 until it reaches the level of the top of pipe 41, at which time float 20 39 will close valve 38. It will be understood that this filling of reservoir 13 also fills pump housing 18 through holes 26, as well as pump return tank 15 and the lower part of water delivery tube 16, the level of the water in housing 18 and tube 25 16 being the same as the level in reservoir 13. Pump motor 20 and fan motor 30 are then set in operation and impeller 22, driven by motor 20, will force water through tank 15 and tube 16 into pan 7, from which latter the water will rain down from nozzles 17 and thoroughly wet coil 10 therebeneath; the water passing through and dripping from the coil being received in catch pan 14 and returned by it to reservoir 13. The operation of fan motor 30 will, of course, rotate fan 28 and thus drive a current of air through coil structure 10 and out through eliminator blades 36. As the water dripping on the coil is of lower temperature than the fluid within the coil and the coil itself, some of the said water will be vaporized and thus serve to reduce the temperature of the coil and the fluid circulating therethrough. The air current from the fan will facilitate this action chiefly by its cooling effect upon the water which is falling from the pan nozzles 17, and the blades 36 of the eliminator will serve to separate most of the globules of water which are entrained by the current from the fan, causing the same to precipitate into catch pan 14 and be returned to reservoir 13. It will be observed that pan 7 extends over the space between fan 28 and coil 10, so that water falling from this portion of the pan will be carried by the air current from the fan against the front and lower part of the coil that is adjacent the fan, thus insuring that said portion of the coil is adequately wetted.

60 The foregoing operation will thus serve effectively to cool the coil and the fluid circulating therethrough with very little loss of water. This is an important industrial economy, not only because water supply is commonly metered and charged for, but also because there is frequently a limit to the amount of water which is available and also a limit, as by ordinance, to the amount that can be discharged into sewage facilities. This saving in water is also promoted by the fact that the nozzle apertures in the bottom of pan 7 are large enough to permit the water to pass therethrough without being atomized, and this size of the said apertures is of importance in that it tends to avoid clogging of the same which, to the extent that it would occur in the case of smaller apertures, would correspondingly reduce the fall of water upon the coil.

70 A feature of great value in this apparatus is

the circulating pump and associated parts which induce such a high rate of circulation of water that maximum heat transfer efficiency is achieved, with the further advantage that the rapid circulation greatly minimizes the deposition upon the surface of the coil of the salts and the like normally present in water, which deposition would materially reduce the effectiveness of the coil and require cleaning or repair thereof. It has been found that the vanes 25 which are positioned above the impeller 22 are very effective in assisting the pumping action in that they are stationary and prevent the impeller action from churning or rotating the water within the pump housing 18; and it has also been discovered that the effectiveness of the pumping action is materially enhanced by positioning the impeller 22 so that it projects into tank 15 whereby its area of rotation is partly within the pump housing 18 and partly within the said tank 15. This projection of the impeller into the tank 15 is preferably to the extent of about ten to thirty percent of the height of the impeller blades. The functional importance of this positioning of the impeller is due mainly to the fact that tank 15 is larger in cross section than and differs in cross sectional shape from the pump housing 18.

Such loss of water as occurs during operation will be automatically replaced by the action of float valve 38, 39, which will permit the inflow of additional water when the level in reservoir 13 is reduced. It is, furthermore, occasionally desirable to drain off some of the water from reservoir 13 in order to prevent too high concentration of salts in the water being recirculated through the apparatus. This drawing off of a portion of the water from the reservoir 13 can be accomplished by manually or automatically opening the electric circuit from the source of power to pump motor 20, whereupon all the water in delivery tube 16 above the level of overflow pipe 41, all the water in pans 7 and 14, and all the water intermediate said pans will return to reservoir 13 and raise the level of water in the latter to a height above the top of overflow tube 41. Should the overflow tube become clogged, the siphon tube will at once become effective and water will be siphoned therethrough from reservoir 13 until the water level is brought down to the extremity of the siphon tube within the reservoir, at which time the siphon action will be broken and the position of float 39 will permit the inflow of a new increment of water to the reservoir. It should be mentioned that the size of the siphon tube and the float valve should be of such relative proportions that the siphon action will withdraw water from the reservoir more rapidly than it is supplied thereto through the float valve.

It is desirable that the pump motor 20 and the fan motor 30 have separate controls so that the pump motor can be stopped not only for the purpose just described but also in order that the water circulation may be stopped while the air circulation is continued when temperature conditions or operating conditions are such that the apparatus effectively performs its cooling function under the influence of the air current alone. And in some cases the reverse may be desired, i. e., that the fan be stopped while the pump continues in operation. In this connection, it will, of course, be understood that condensers of this type, especially when used in refrigerating systems, are normally required to operate intermittently rather than continuously; and that, as

already indicated, the action of both the pump motor and the fan motor may be subjected to manual control and/or to automatic control by pressure or temperature actuated switches.

Turning now to the modified form of the invention shown in Figs. 5 and 6, the constructional parts are the same as hereinabove described in connection with the form shown in Figs. 1 to 4 with the exception of the pump mechanism which is somewhat different in construction and arrangement and operates on the water pulling principle rather than on the pushing or thrusting principle.

In this form of Figs. 5 and 6, the cylindrical pump housing is denoted by 43 and it uprises directly from the bottom of reservoir 13 and extends substantially to the top of the casing where it is capped by a T-coupling 44, the horizontal branch 45 of which is suitably connected, as by bolted flanges, to a mouth piece 46 on the water distributing pan 7. An electric motor 47, which corresponds to the motor 20 of the form shown in Figs. 1 to 4, has its base 48 resting on coupling 44, and the motor drive shaft 49 extends downwardly within pump housing 43 almost to the bottom thereof. Three impellers denoted by 50, 51 and 52, which are similar to impeller 22, are fixed to shaft 49; and three sleeves 53, 54, 55, which are like sleeve 23 with its hub and vanes, are rigidly positioned within housing 43 closely above impellers 50, 51 and 52 respectively. Two sets of circumferential holes 56 and 57 are formed through pump housing 43 below impeller 50. As this shaft 49 is quite long, it is desirable that the hub of at least one sleeve, e. g., 54, be of such size as to serve as a bearing therefor.

In the operation of this form of the invention shown in Figs. 5 and 6, the reservoir 13 is supplied with water as heretofore described in connection with the form shown in Figs. 1 to 4 and the pump motor 47, as well as the fan motor 30, are started. The rotation of the shaft 49 of motor 47 causes impeller 50 to draw water up within pump housing 43 until the water reaches the height of impeller 51, at which time the latter adds its drawing effect on the water, which continues to be drawn up within the pump housing until it reaches impeller 52, at which time all three impellers are acting on the column of water and force the same into the water distributing pan 7, whence it rains down upon the coil and is in the main returned to the reservoir 13 as heretofore described in connection with the form shown in Figs. 1 to 4. It will be observed that the sleeves 53, 54, 55, with their radiating vanes, are located above the impellers, as in the case of the form shown in Figs. 1 to 4, notwithstanding the column of water is moving upward in pump housing 43 of the modified form of invention shown in Figs. 5 and 6 instead of downward as in the previously described form. However, the effect of the vanes in the said sleeves is the same in the form shown in Figs. 5 and 6 as in the first described form and the operation of the invention and its functional effects are also the same. The ceiling brackets 58, 59, which are secured to the top of the apparatus casing in the form shown in Figs. 5 and 6, are different in shape from the brackets shown in Figs. 1 and 2 in order to space pump motor 47 from the ceiling. It may be added that the pump motor and fan motor of the form shown in Figs. 5 and 6 may be manually and/or automatically controlled, as set forth in the description of the preceding form of the invention.

Referring now to the second modified form of the invention which is shown in Figs. 7 and 8, this embodiment is designed for floor installation and differs in a number of respects from the previously described forms, although the pumping mechanism, which is the most important feature of the invention, is similar to that of Figs. 1 to 3.

In this modified form of Figs. 7 and 8, the casing is oblong in cross section, and comprises a front 60, a back 61, sides 62, 63, and bottom 64, which are preferably composed of materials such as galvanized sheet plates secured together in any suitable manner, as by welding or riveting; the bottom being provided with legs 65, preferably of angle iron.

The upper part of the casing houses a pair of blowers 66, 66, which may be of any well-known or approved form and be secured within the casing in any appropriate manner, the fans of the said blowers (not shown) being rotated by a shaft 67, which is driven by a motor 68, carried by a bracket 69, through belt and pulley mechanism 70.

A set of eliminator blades 71 is fixed in the casing below the blowers by angle irons 72 that are fastened to the sides 62, 63, of the casing; and a coil 73, which has an inlet pipe 74 and a discharge pipe 75, is mounted about midway between the top and bottom of the casing by header plates 76, 77, which extend transversely of the casing and are suitably attached to its front and back.

The water circulating means which, as already indicated, is similar to that shown in Figs. 1 to 3, includes a cylindrical pump housing 78 that uprises from a reservoir 79 which is formed in the lower part of the casing. The housing is provided with a series of water inlet holes 80 and a vane sleeve 81, which is like sleeve 23, 24, 25, and is fixed in the housing below the said holes. A motor 82 surmounts housing 78 and its shaft 83 carries an impeller 84 which is located at the bottom of the housing and extends partly into a pump return tank 85 that is connected with one end of the pump housing. A water delivery tube 86 is connected with the other end of tank 85 and extends upwardly within the casing to a point intermediate the eliminator and the coil, where it connects with a manifold 87 from which project laterally a set of closed end water distributing pipes 88 that are provided with perforated nozzles along their lower surfaces, corresponding to nozzles 17 shown in Figs. 1 and 2. If desired, the tube 86 may be secured by any suitable means to the side 62 of the casing, and the pipes 88 may also be secured to each other and to the front 60 and back 61 of the casing by brackets or other equivalent means. The reservoir 79 has an overflow pipe 89 which pierces its bottom at 90, a water inlet pipe 91, a float valve 92, and a siphon tube 93, which are similar to the corresponding parts shown in Fig. 1. The front of the casing is provided with a metal air inlet grill 94 which permits air to be drawn into the casing, past the coil, water distributing pipes and eliminator, and be ejected at the top of the casing through the blower mouths.

The operation or functioning of this form of the invention shown in Figs. 7 and 8 is generally the same as that hereinabove described except that the suction generated by the blowers 66, 66, is substituted for the air stream generated by the fan 28, while the water falling from the distribution pipes 88 and dripping from the coil 73, and eliminator 71 passes directly into the reservoir 79 instead of being caught in a pan and returned to the reservoir. As in the case of the previously described forms, the motors 68 and 82 of this second modified form may be independently controlled manually and/or automatically.

The third modified form of the invention, which is illustrated in Fig. 9, differs from the form shown in Figs. 7 and 8 in substantially the same way that the form shown in Figs. 5 and 6 differs from the form shown in Figs. 1 to 4, i.e., the water pump of the form shown in Fig. 9 operates on the pulling rather than on the pushing or thrusting principle. In this form the pump housing is marked 95 and its lower end positioned in the reservoir 79 has two sets of water inlet holes 96, 97. The upper end of the housing is connected by a T-coupling 98 with the mouth 99 of manifold 87, and the pump motor, here marked 100, surmounts coupling 98 while its shaft 101 projects downwardly through three vane sleeves 102, 103, 104, that are fixed within housing 95 and are like sleeve 23, 24, 25, with at least one sleeve, e.g., 103, serving as a bearing for the shaft. Three impellers 105, 106, 107, are fixed on shaft 101 below said sleeves and their action, when rotated by motor 100, is like that of impellers 50, 51 and 52, as described in connection with the form of the invention shown in Figs. 5 and 6.

With reference to all the forms of the invention, it will be seen that it provides for a very efficient and rapid circulation and recirculation of water, as well as efficient cooling of the fluid within the evaporator, the function or result being accomplished with great economy of water and power and with avoidance of clogging the water distributing elements and the formation of undesirable deposits upon the coil; while such additional supply of fresh water as is desirable either for the purpose of replenishing the slight loss, or diluting the salt concentration, is automatically furnished.

It will be understood that various changes may be resorted to in the form, construction, material and arrangement of the parts without departing from the spirit or scope of the invention; and hence I do not intend to be limited to details herein shown or described except as they may be included in the claims or be required by disclosures of the prior art.

What I claim is:

1. Apparatus of the character described comprising, a coil, a water reservoir, a conduit for distributing water from the reservoir to the outer surface of the coil, and pumping mechanism adapted to cause water to flow from the reservoir through said conduit, said pumping mechanism comprising, a housing having a water inlet in the side thereof, a motor drive shaft within the housing, an impeller fixed to the shaft, and at least one vane positioned within the housing adjacent the impeller and lying in a plane substantially parallel to the longitudinal axis of the shaft to resist swirling of the water within the housing when the impeller is rotated.

2. Apparatus of the character described comprising, a coil, a water reservoir, a conduit for distributing water from the reservoir to the outer surface of the coil, and pumping mechanism adapted to cause water to flow from the reservoir through said conduit, said pumping mechanism comprising, a housing having a water inlet in the side thereof, a motor located at the top of the housing, a drive shaft extending from

the motor downwardly within the housing, an impeller fixed to the shaft, and at least one vane positioned within the housing adjacent the impeller and lying in a plane substantially parallel to the longitudinal axis of the shaft to resist swirling of the water within the housing when the impeller is rotated.

3. Apparatus of the character described comprising, a coil, a water reservoir, a conduit for distributing water from the reservoir to the outer surface of the coil, and pumping mechanism adapted to cause water to flow from the reservoir through said conduit, said pumping mechanism comprising, a housing having a water inlet in the side thereof, a tank at the lower end of the housing, a motor drive shaft within the housing, and an impeller fixed to the shaft and positioned partly within the housing and partly within the tank.

4. Apparatus of the character described comprising, a coil, a water reservoir, a conduit for distributing water from the reservoir to the outer surface of the coil, and pumping mechanism adapted to cause water to flow from the reservoir through said conduit, said pumping mechanism comprising, a housing having a water inlet in the side thereof, a tank at the lower end of the housing, said tank being of greater cross sectional area than the housing, a motor drive shaft within the housing, and an impeller fixed to the shaft and positioned partly within the housing and partly within the tank.

5. Apparatus of the character described comprising, a coil, a water reservoir, a conduit for distributing water from the reservoir to the outer surface of the coil, and pumping mechanism adapted to cause water to flow from the reservoir through said conduit, said pumping mechanism comprising, a housing having a water inlet in the side thereof, a tank at the lower end of the housing, said tank being of greater cross sectional area than the housing, a motor drive shaft within the housing, and an impeller fixed to the shaft and positioned partly within the housing and partly within the tank.

6. Apparatus of the character described comprising, a coil, a water reservoir, a conduit for distributing water from the reservoir to the outer surface of the coil, and pumping mechanism adapted to cause water to flow from the reservoir through said conduit, said pumping mechanism comprising, a housing having a water inlet in the side thereof, a tank at the lower end of the housing, said tank being of greater cross sectional area than the housing, a motor drive shaft within the housing, and an impeller fixed to the shaft and positioned partly within the housing and partly within the tank, the projection of the impeller into the tank being less than one half the vertical height of its blades.

7. Apparatus of the character described com-

prising, a coil, a water reservoir, a conduit for distributing water from the reservoir to the outer surface of the coil, and pumping mechanism adapted to cause water to flow from the reservoir through said conduit, said pumping mechanism comprising, a housing having a water inlet in the side thereof, a tank at the lower end of the housing, said tank being of greater cross sectional area than the housing, a motor drive shaft within the housing, and an impeller fixed to the shaft and positioned partly within the housing and partly within the tank, the projection of the impeller into the tank being less than one half the vertical height of its blades.

8. Apparatus of the character described comprising, a coil, a water distributor located above the coil, a water reservoir, a conduit connecting the distributor with the reservoir, a pump adapted to cause water to flow from the reservoir to the distributor, and means for forcing a current of air to and through the coil structure in a direction at an angle to the direction in which water from the distributor traverses the coil, the water distributor being so positioned as to extend over an area in front of the face of the coil toward which the air current moves so that water falling from the said extension of the distributor will be carried by the air current against the said face of the coil.

9. Apparatus of the character described comprising, a coil, a water reservoir, a conduit for distributing water from the reservoir to the outer surface of the coil, and pumping mechanism adapted to cause water to flow from the reservoir through said conduit, said pumping mechanism comprising, a tank having a water inlet and a water outlet, a power rotated impeller at the water inlet of the tank, and at least one vane positioned at the upstream side of the impeller to resist swirling of the water drawn toward the impeller by its rotation.
